Letters Patent

The schedule referred to in these letters patent and making part of the same, containing a description in the words of the said Mr. H. C. Simpson himself of his improvement ^{in the} art of cleaning wool from burs and other foreign substances.

To all persons to whom these presents shall come: Be it known that I, H. C. Simpson, of the City of Boston, County of Suffolk, State of Massachusetts, merchant, have invented a new and useful improvement in the art of cleaning wool from burs and other foreign substances and that the following is a full and exact description of the construction and use of said improvement: The construction of the machine is as follows: The frame six feet long, three feet high, and four feet wide, should be made stout and strong, the part upon which the wool is placed when the burs are in it is called a feed frame upon which sits upon the frame of the machine and is in every respect like the feed frame of a carding machine which is so well known to mechanics as to be unnecessary to describe it; the feed frame is fastened at, upon the drawing a small cylinder number B, is placed horizontally across the frame next to the feed roller is the feed frame, this cylinder should be made best when about eighteen inches diameter and with cards upon it of No. 26 or 28 wire gauge thickness and teeth four or cleaner as placed across the frame opposite to the said cylinder B, secured to work well when twelve inches diameter to be armed with six rows of teeth about

half an inch long & stout as a sailor needle, set half an inch apart. A clipper frame marked P , is seen on the drawing without the feed frame; this is similar to clothing shears, being a frame of cast iron with a blade with a round edge turned, mounted upon it, & a spiral shear set in box, & adjustable to the card for operation by screws which place it nearer or farther from the card as may be required to perform more perfectly in detaching the burrs. Motion is given to the main drawing pulley H by steam, water, or animal power, the pulley G on the same shaft drives the shaft A , which has upon it two pulleys, one to drive the pulley clipper marked I , which being large and communicating to a small pulley on the clipper drives it with great power rapidly. The other pulley marked K , communicates to the fan which also rotates rapidly. The speed from my experiments, should be about two hundred revolutions a minute to the card cylinder - the clipper about twenty five hundred times a minute, and the fan fast enough to clean the card cylinder having described the construction of the machine which will of course be varied to suit the different species of the operators, I now describe the use of said machine - wool from South America and indeed most all wools have more or less of a vegetable substance called burs so attached to it, that it is not taken out by washing and therefore the only mode of cleaning the wool has been by hand until about two years since a Mechanick of the City of Boston Mr. Samuel Brilliard B invented a machine for the purpose which performed the part of taking out the burs very well - but was set aside from the injury. The staple see C , The machine for which I now ask a patent performs the work of taking out the burs without any injury to the fibre, The wool should The wool should in the first place be well picked by

downward wool-picker, with the burs in it, and in this state the machine receives it, it is placed by the operator in the feed belt which when the machine is in operation is conducted to the draw rolls which revolve very slow, and as the wool is carried through the draw rolls with so much greater rapidity than the feed rolls and carries it in a downward direction by the clipper frame which is placed nearly in contact with the surface of the teeth - the burs etc all foreign substance are stripped by the blade in the clipper frame and the swift revolutions of the clipper knock them off. The wool continues in the teeth of the card cylinder and is separated by the fan which is placed upon the opposite side to the clipper frame - as by the fan blown or taken from the cylinder and deposited in a clean state in the room which may be made for the purpose. It can be seen by any one acquainted with machinery that the application of knocking the burs from card teeth may be used by machines of different construction from this, I have myself used it in a variety of ways by placing the clipper frame on the main cylinder of a common card machine, or by affixing a machine like the one here described to the end of a carding machine, the defter of which to feed the cylinder instead of a feed frame, and also to place the clipper frame upon the tumblers of a card machine, knocking off the burs, and then go immediately to the main cylinder to be carded, all these applications work well, and two or three of them are now used by me. I therefore do not claim as my invention any particular form of machinery to effect the object of detaching burs or other foreign substance from wool, but claim the application of knocking, blowing, brushing, or striking burs or other foreign substance from the surface of card teeth or any other kind of teeth. I

forward herewith to the Patent office of the United States, and making part by way of illustration of the principles of this my specification, a small model of the same whereby the use, application, & construction of my said improvement, are distinctly and accurately shown, to the end that the said model may be kept in said office, in evidence of this my invention and as belonging to and making part of this my specification. It being understood that the principle of my said invention is alone illustrated by said model. The annexed drawing to which my specification refers, presents two views of the machine and may assist the examiner to better understand the specification.

In testimony that the foregoing is a true specification of my said improvement as above described, I have hereunto set my hand this eleventh day of June eighteen hundred and thirty five,
